ALICE BUDD RIDABOCK, OF STAMFORD, CONNECTICUT

HOLDING DEVICE FOR NECKLACES

Application filed February 9, 1927. Serial No. 166,888.

This invention relates to holding devices for necklaces.

One of the objects thereof is to provide a simple and practical device for holding the loops of a necklace in predetermined relation.

Another object is to provide a device of the above nature which shall be positive in action and convenient in use. Another object is to provide a device of the above nature of an attractive appearance and so formed as to preclude the chance of injury to the necklace. Other objects will be in part obvious and in part pointed out hereinafter.

The invention accordingly consists in the features of construction, combinations of elements and arrangements of parts which will be illustratively herein set forth and the scope of the application of which will be indicated in the following claims.

Referring now to the accompanying drawings in which is shown one of various possible embodiments of this invention,

Figure 1 is a diagrammatic view of the loops of a necklace indicating the preferred point of application of the device;

Figure 2 is a rear view of the several strands of the necklace showing the device in position;

Figure 3 is a side elevation of the device in operative position with the related parts and showing in dotted lines its released or opened position; and

Figure 4 is a sectional view upon a much enlarged scale taken at the central portion of the line 4-4 in Fig. 2.

Similar reference characters refer to similar parts throughout the several views of the drawings.

As conducive to a more ready understanding of the features of this invention, it may be noted that in the use of necklaces, when they are looped a number of times about the neck of the wearer there is a tendency of the larger loop or loops, due to their greater weight, to become still larger, thus tightening the smaller loop or loops about the neck with a consequent discomfort to the wearer and detraction from the attractiveness of the appearance of the necklace. Also, although of less importance, with a looped necklace, particularly

when formed of pearls or the like, the individual loops at the back of the neck gather together and rub one against the other with a chance of injury to the pearls or beads.

The avoidance of these defects in a practical and convenient manner without chance of injury to the members of the necklace is among the dominant aims of this invention.

Referring now to the drawings in detail, it is to be understood that the necklace may be looped a number of times about the neck, the arrangement being here shown as comprising the loops 1, 2 and 3. This arrangement gives at the back of the neck of the wearer the three similarly numbered strands superposed one over the other as shown in Fig. 2 of the drawings.

Coacting with these strands, and equally adapted for coaction with two strands only, is a device 4 the construction of which is shown more in detail in Figs. 3 and 4. This device comprises the lower or inner member 5 and the upper or outer member 6 hinged one to another as at 7. At the opposite ends of these members there is provided on part 6 a loop 8 and on the part 5 a projection 9 adapted to snap into the loop and hold the parts in the closed position shown in the drawings.

The part 5, as shown in cross-section in Fig. 4, may be of a hollow metal construction and converges preferably along the curved lines 10 to a narrow edge-like form 11 where it embraces the cord 12 of the necklace. It may here be noted that certain features of this invention are applicable to a necklace which is not of the beaded form, although many of them relate particularly to a string of beads, using the term "bead" in a broad sense to include pearls or elements of like nature. The portion 13 is preferably flattened as indicated and of broad form to adapt it to rest against the neck of the wearer and to tend to support the entire device in a position extending directly outward therefrom.

Stretched about the part 5 where it enters between the beads, and extending over its narrow portion, is preferably provided a coating of chamois skin or the like, as indicated at 14, so as to avoid the chance of injury to

the beads and to give a yielding surface which when clamped into position will tend by its reaction to hold the prong 9 within the loop 8. The free edges of this covering 14 are preferably seated and gripped within recesses 15 formed in the part 5, and it is also preferably cemented to the surface which it contacts.

Considering now the part 6, as shown in cross-section in Fig. 4, it is of a conformation generally similar to the part 5 except that its outermost portion 16 is of a curved and ornamental form and may be provided with any desired type of ornamentation. This member 6 is also covered at its inner portions with chamois, as indicated at 17, and the edges of the latter are gripped as indicated at 18.

Recurring to Fig. 3 of the drawings, the contiguous surfaces of the members 5 and 6 are provided with oppositely disposed recesses 19 and 20 at spaced portions so as to embrace the string or thread 12 at the several points at which it encircles the neck. Between these recesses, however, the members 5 and 6 come substantially into contact one with the other in such manner as by compressing the chamois or other yielding covering to give to the device such reaction as will prevent it from accidental opening.

When it is desired to remove the device, the parts are opened as indicated in dotted lines in Fig. 3, and when it is placed in position the proper spacing of the individual strands of loops is facilitated by the spacing of recesses 19 and 20 above described and inclination of the former.

The use of the device will readily be understood from the foregoing, and it may be noted that when the necklace is in the form of beads, it is quite unnecessary to grip the central thread, for if each loop is given the desired length, then when this holding device is placed in position, the proper number of beads will be maintained in each loop and the individual loops can not vary substantially in length even though the thread 12 be slidable within the holding device.

It will thus be seen that there has been provided a device in which the several objects of this invention are achieved; that it does not detract from the appearance of the necklace and is well adapted to withstand the conditions of hard practical use without injury to itself or the parts with which it is employed.

As various changes might be made in the construction herein set forth and as the invention might be embodied in a number of forms, it is to be understood that the description herein set forth and the drawings associated therewith are to be considered merely as illustrative and not in a limiting sense.

I claim as my invention:—

1. In a clasp for necklaces comprising a string of beads in which the adjacent beads

are held against substantial separating movement lengthwise of the string, a pair of members adapted to receive therebetween a plurality of overlapping portions of the necklace and adapted to engage the beads of the necklace to hold said overlapping portions against movement lengthwise relative to one another, said members being movable toward and away from each other for insertion and removal of the necklace, a catch for holding said members together and in operative position upon the necklace, and a covering of soft resilient material upon a surface of said members which comes into engagement with the beads, the spring action of said covering against the necklace tending to urge said members apart and thereby tending to hold said catch closed.

2. In a clasp for necklaces comprising a string of beads in which the adjacent beads are held against substantial separating movement lengthwise of the string, a pair of members adapted to receive therebetween a plurality of overlapping portions of the necklace and adapted to engage the beads of the necklace to hold said overlapping portions against movement lengthwise relative to one another, said members being movable toward and away from each other for insertion and removal of the necklace, each of said members having a soft covering for engaging the beads, and a catch for holding said members together and in engagement with said beads, said catch in order to be released requiring a movement of said members toward each other beyond normal operative position.

3. In a clasp for necklaces comprising a string of beads in which the adjacent beads are held against substantial separating movement lengthwise of the string, a pair of members adapted to receive therebetween a plurality of overlapping portions of the necklace and adapted to engage the beads of the necklace to hold said overlapping portions against slipping lengthwise relative to one another, said members being movable toward and away from each other for insertion and removal of the necklace, each of said members having a covering of soft sheet material for engaging the beads, said covering being held in place by portions of the members being bent over to clamp the edge portions of the sheet material.

4. In a device of the class described, a necklace comprising an endless string of beads, said beads being in substantial abutment one with another and thereby holding each other against substantial longitudinal movement on the string and the necklace being arranged in a plurality of loops of different sizes, each of said loops being adapted to encircle the neck of the wearer, and a detachable device positioned upon said necklace at the portions thereof adapted to rest against the back of the neck, said device comprising a pair of mem-

bers between which the string of each of said plurality of loops passes at the portions back of the neck and having parts entering into engagement with the beads to prevent slipping of said loops longitudinally relative to one another and to thereby maintain said loops of predetermined size.

5 In testimony whereof, I have signed my name to this specification this first day of February, 1927.

10 ALICE BUDD RIDABOCK.
